Primary Examiner — Paula Greene(74) Attorney, Agent, or Firm — C. G. Mersereau; Nikolai & Mersereau, P.A.(57) CLAIM

The ornamental design for a handle for hand tools, as shown and described.

DESCRIPTION

FIG. 1 is a perspective view of a handle for hand tools, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof; and,

FIG. 9 is an operational view showing the handle mounted with a shaft of a hand tool.

In the drawings, the broken lines are shown for illustrative purposes only and form no part of the claimed design.
